(57) **CLAIM**

The ornamental design for a cookware handle as shown and described.

DESCRIPTION

FIG. 1 is a perspective view of the claimed design, according to a first embodiment;

FIG. 2 is a left side view thereof;

FIG. 3 is a right side view thereof;

FIG. 4 is a top view thereof;

FIG. 5 is a bottom view thereof;

FIG. 6 is a front view of thereof; and,

FIG. 7 is a back view thereof.

The ornamental design that is claimed is shown in solid lines in the figures. Broken lines formed by equal or substantially equal length dashes show unclaimed portions of the design and form no part of the claimed design. Broken lines formed of unequal length dashes (i.e. dash-dot) show boundaries between claimed and unclaimed portions of the design.
